UNITED STATES PATENT OFFICE

FRANK HAVEL, OF CHICAGO, ILLINOIS, ASSIGNOR TO S. KARPEN & BROTHERS, A CORPORATION OF VIRGINIA

DESIGN FOR A CHAIR OR SIMILAR ARTICLE

Application filed December 28, 1929. Serial No. 33,967. Term of patent 3½ years.

To all whom it may concern:

Be it known that I, FRANK HAVEL, a citizen of the United States, residing at Chicago, in the county of Cook and State of Illinois, have invented a new, original, and ornamental Design for a Chair or Similar Article, of which the following is a specification, reference being had to the accompanying drawing, forming a part thereof.

The figure is a perspective view of the chair, showing my new design.

I claim:

The ornamental design for a chair or similar article, as shown.

In witness whereof, I hereunto subscribe my name this 20 day of December, 1929.

FRANK HAVEL.
